UNITED STATES PATENT OFFICE.

CARL A. FRAHM, OF CANTON, OHIO.

DESIGN FOR A SPICE SET.

Application filed February 3, 1923. Serial No. 5,066. Term of patent 3½ years.

To all whom it may concern:

Be it known that I, CARL A. FRAHM, a citizen of the United States, residing at Canton, in the county of Stark and State of Ohio, have invented a new, original, and ornamental Design for a Spice Set, of which the following is a specification, reference being had to the accompanying drawing, forming a part hereof.

The figure is a front perspective view of the spice set showing my new design.

The improved spice set is manufactured and sold as a unitary structure.

I claim:—

The ornamental design for a spice set, as shown.

CARL A. FRAHM.
